CONTROL FOR PRESSING MACHINES

James M. Dewey, Cincinnati, Ohio, assignor to
The American Laundry Machinery Company,
Norwood, Ohio, a corporation of Ohio

Application October 23, 1935, Serial No. 46,244

12 Claims. (Cl. 38—25)

This invention relates to a pressing machine and more particularly to improvements in operating and control mechanism therefor.

My improved control mechanism is applied 5 to a pressing machine in which two coacting pressing members are relatively moved toward each other in two steps, a first step into preliminary or safe closed position and a second step into final closed position. In such a pressing machine I provide power means for causing the relative approach movement between the pressing members with a control member for each step of the operation and improved mechanism for causing the operation of the second 10 step control member to follow automatically the operation of the first step control member.

Another feature of my invention is the provision in a press of the type above described of a power device for actuating the second step control member together with means for actuating that power device simultaneously with the production of the first step of the closing operation. My invention also provides a time delay period 15 between the actuation of a first step control member and the operation of the power device for causing second step operation of the press closing mechanism.

Other features of my invention include the novel arrangement of certain portions of the 20 control mechanism to carry out the above described functions and the advantages of these various constructions will be pointed out as the description proceeds.

In the drawings, Fig. 1 is an end elevation 25 partly in section of a pressing machine embodying my invention with the press parts in open position and with the control mechanism shown diagrammatically; Fig. 2 is a view similar to Fig. 1 showing the press parts in closed position.

While my invention may be applied to a pressing machine in which one of a pair of coacting pressing members is held stationary while the other member is moved by two step operation into engagement therewith, I have chosen to illustrate my invention as applied to a pressing machine in which each of the coacting pressing members is movable toward the other. The embodiment shown comprises a frame 10 supporting on a suitable bracket a pressing bed 11 movable vertically relative to the frame and guided during such movement by one or more suitable pins 11a which slidably engage a portion of the frame. On a bracket of the frame is pivotally mounted a head lever 12 at the forward end 30 of which is carried a pressing head 13 for move-

ment into and out of coacting position with the bed 11. The head may be suitably heated if desired. The pressing head is moved to position adjacent the bed by a pair of toggle links 14 and 15 connected between the rear end of the head lever and the lower rear portion of the frame. The toggles are biased toward broken position by a spring 16 and are moved into and beyond straightened position by a cylinder and piston motor 17. This motor comprises a cylinder 17a housing a piston 17b whose rod 17c is connected with the toggle links. The links are limited in their movement rearwardly by mutually engaging abutments 14a and 15a. A combined snubber and toggle kicking device 18 is 10 supported on a suitable bracket and includes a plunger 18a spring pressed outwardly.

The means for raising the pressing bed into final engagement with the head after the latter has been placed in position adjacent it comprises a cylinder and piston motor 19 mounted on 15 the frame. This motor comprises a cylinder 19a housing a piston 19b whose rod 19c operatively engages the bed.

Motive fluid is supplied to motor 17 from a 20 source of pressure fluid, such as conduit 20, and thence by way of valve casing 21, conduit 22, valve casing 23 and conduit 24 to cylinder 17a. Valve casing 21 houses a normally closed inlet valve 21a having a stem 21b by which it may be actuated. Valve casing 23 houses a valve disk 23a which in its normal position as shown in Fig. 1 normally opens an outlet port 23b while closing an inlet port 23c but when actuated the valve disk closes the outlet port 23b and opens the inlet port. The valve disk is actuated by a stem 23d and a manual 23e.

Motive fluid is supplied to motor 19 by way 25 of conduit 25, valve casing 26 and conduit 27. Casing 26 houses a normally open outlet valve 26a and a normally closed inlet valve 26b mounted on a common stem 26c by which the valves 30 may be actuated.

A power device indicated generally at 28 is 35 provided for actuating the control valves in casing 26. This power device provides a differential piston construction including a piston 28a of greater diameter and a piston 28b of lesser diameter rigidly connected by a rod 28c. This rod carries a pin 28d which engages bellcrank 29 and more particularly the pin enters an elongated slot 29a in the bellcrank. The device 28 has suitable cylinder portions 28e housing piston 28a and 28f housing piston 28b which are rigidly connected together by an intermediate housing 40 45 50 55

portion which is cut away at 30 to permit operation of the bellcrank. Fluid for operation of the power device 28 is provided by way of conduit 31, valve casing 32, conduit 33, valve casing 34 and conduit 35. In conduit 35 is located an adjustable restricted orifice 36 which may be in the form of an adjustable needle valve as shown. Valve casing 32 houses a valve 32a which is adapted to open and close a port 32b 10 in communication with cylinder 28f. This valve is biased in port closing direction by a spring 32c and the valve is guided and actuated by a stem 32d which has a sliding fit with a suitable bore in piston 28b. The spring 32c is strong 15 enough to preponderate over supply pressure entering through conduit 31 and exerted against the inner face of the disk 32a. Valve casing 34 houses a valve disk 34a which normally closes an outlet port 34b as shown in Fig. 1 but when actuated opens this outlet port and closes the normally open inlet port 34c. The valve disk 34a is actuated by a stem 34d which is rigidly connected by a bracket 37 with the valve stem 21b. Both of these valve stems may be actuated simultaneously therefore by movement of manual 38.

A press opening supply of fluid for the power device 28 is supplied through conduit 39, valve casing 40 and conduit 41. Casing 40 houses a normally closed inlet valve 40a mounted on a 30 stem 40b and actuated by a manual 40c.

With the parts in the position of Fig. 1, the operator arranges the lay of the work upon the bed 11 and actuates manuals 23e and 38 to the position shown in Fig. 2. This supplies motive fluid to motor 17 through conduit 20, valve 21a, conduit 22, valve 23a and conduit 24. Piston 17b makes a stroke rearwardly or to the left as viewed in the drawings, which moves the toggle links 14 and 15 to beyond straightened position thus placing the pressing head 13 in the position shown in Fig. 2, although it will be understood that as the pressing head reaches this position the bed is still in the position of Fig. 1.

Normally the power device 28 is in the position 45 shown in Fig. 1 because motive fluid under equal pressure is applied against the faces of pistons 28b and 28a and the piston 28a being of greater area the combined piston device and rod 28c moves to the right and remains in the position 50 of Fig. 1 as the force exerted on piston 28a is greater than the force exerted by spring 32c. Upon actuation of manual 38 as above described, the inlet port 34c is closed, thus cutting off the fluid supply for cylinder 28e. At the same time outlet 55 port 34b is opened so that evacuation of cylinder 28e is initiated. This evacuation takes place at a restricted rate because of the needle valve 36 and it will be understood that this rate can be controlled by the adjustment of the needle valve. 60 It follows therefore that after a suitable timed delay the pressure against piston 28b preponderates over the pressure exerted against piston 28a and the two pistons and their connecting rod 28c move toward the left into the position of Fig. 2. As the parts move over, spring 32c closes valve 32a and when the pistons reach the position of Fig. 2 bell crank 29 is moved clockwise sufficiently to actuate the valves in casing 26 thus 65 effectively supplying motive fluid to motor 19 and raising bed 11 into pressure engagement with the head 13. The operator may then release manuals 23e and 38 and the press will remain closed. Release of manual 38 again opens the inlet port 70 75 34c but this is ineffective to supply fluid to cyl-

inder 28e because valve 32a is in series in the supply line 33 and at this time cuts off supply.

The purpose of the time delay caused by the needle valve 36 is to insure that motor 17 will move the links 14 and 15 to the strut forming position shown in Fig. 2 where they resist counter-clockwise movement of lever 12 upon pressure engagement of bed 11 against the head 13. The release of manuals 23e and 38 evacuates cylinder 17a but the parts remain in the position of Fig. 2 because the upward pressure of the pressing bed holds the toggle links in their beyond straightened position.

To open the press manual 40c is actuated thus supplying fluid through conduit 39, valve 40a and 15 conduits 41 and 35 to cylinder 28e. The pressure against piston 28a then preponderates over the force exerted on piston 28b and returns the parts of the power device 28 to the position shown in Fig. 1 whereupon the valves in casing 26 are 20 returned to their normal position as shown in Fig. 1 by the actuating spring and cylinder 19a is evacuated. Bed 11 then moves down due to the action of gravity and the toggle links are moved toward their broken position by the combined 25 action of the kick device 18 and spring 16.

It will be understood that in actual construction the manuals 23e and 38 are placed at the front of the press in position before the operator and so spaced apart that they require a hand of 30 the operator on each of them for their actuation. I thus provide a safe control mechanism for a 35 pressing machine of this type which prevents injury to an operator's hands because both manuals 23e and 38 must be actuated to supply power to the head moving motor 17 and one of these safety control members initiates the raising of the bed which finally closes the press.

What I claim is:

1. In a pressing machine, a pair of coacting 40 relatively movable pressing members, power means for causing relative approach movement between said members in two steps, a first step into preliminary closed position and a second step into final closed position, control members for 45 said power means, one control member for causing each step of the operation thereof, a power device for actuating and holding actuated said second step control member, and means for actuating said power device by operation of said first 50 step control member, said last named means including an arrangement for delaying operation of said device for an interval after operation of said first step control member.

2. In a pressing machine, a pair of coacting 55 pressing members, each movable toward the other, power means for moving one of said members into pressing position adjacent the other member, said means including parts constructed and arranged so that said one member when in 60 pressing position resists pressure against it, a control member for said power means, power means for moving said other member into engagement with said one member, a control member for said last named power means, a power 65 device for operating said last named control member, and means for actuating said power device by movement of said first named control member into power supply position.

3. In a pressing machine, a pair of coacting 70 relatively movable pressing members, power means for causing relative approach movement between said members in two steps, a first step into preliminary closed position and a second step into final closed position, control members for 75

said power means, one control member for causing each step of the operation thereof, a power device for actuating and holding actuated said second step control member, said device being biased in control member actuating direction, fluid means normally holding said device against the force of its biasing means, and means for exhausting fluid from said fluid means by actuation of said first step control member.

5 10. 4. The combination of claim 3, and in which said exhausting means includes a restricted orifice for delaying exhaust from said fluid means.

5 15. 5. The combination of claim 3, and in which said fluid means includes a supply conduit, a normally open valve therein, and means for closing said valve upon movement of said device in second-step-control-member-actuating direction.

6 20. 6. In a pressing machine, a pair of coacting relatively movable pressing members, power means for causing relative approach movement between said members in two steps, a first step into preliminary closed position and a second step into final closed position, control means for said power means including two spaced safety control members for controlling first step operation of said power means, a second step control member for said power means, a power device for actuating said second step control member, means biasing said device in control member actuating direction, fluid means normally holding said device against the force of its biasing means, a normally closed outlet valve for exhausting said fluid means, and an operative connection between said valve and one of said safety control members for opening said valve by actuation of the said safety control member.

7 25. 7. In a pressing machine, coacting head and bed pressing members, each movable toward the other, a first motor and mechanism associated therewith for moving said head into position adjacent said bed, said mechanism being arranged to hold said head in said position in resistance to pressure from said bed, a second motor for moving said bed into engagement with said head when the latter is in said adjacent position, a control member for said first motor, and means independent of said first motor for actuating said second motor in press-closing direction by movement of said control member in press-closing-producing direction.

50 8. A pressing machine as in claim 7, and in which said last named means includes means for delaying actuation of said second motor following movement of said control member.

55 9. In a pressing machine, coacting head and bed pressing members, each movable toward the other, a first motor and mechanism associated therewith for moving said head into position adjacent said bed, said mechanism being arranged to hold said head in said position in resistance to pressure from said bed, a second motor for moving said bed into engagement with said head when the latter is in said adjacent position, a control member for each motor, a device for actu-

ating said second motor control member, said device including mutually opposed movable abutments of greater and lesser areas adapted as one preponderates over the other to move said device into positions corresponding to "off" and "on" positions respectively of said control member, fluid supply lines for conducting pressure fluid against each of said abutments, said supply line for said abutment of greater area including a normally closed outlet valve, and means for opening said outlet valve coincidently with movement of said first motor control member in motor energizing direction.

10 15. 10. In a pressing machine, coacting head and bed pressing members, each movable toward the other, a first motor and mechanism associated therewith for moving said head into position adjacent said bed, said mechanism being arranged to hold said head in said position in resistance to pressure from said bed, a second motor for moving said bed into engagement with said head when the latter is in said adjacent position, a pair of spaced safety control members adapted upon simultaneous actuation to energize said first motor, a second motor control member, a device for actuating said second motor control member, said device including mutually opposed movable abutments of greater and lesser areas adapted as one preponderates over the other to move said device into positions corresponding to "off" and "on" positions respectively of said control member, fluid supply lines for conducting pressure fluid against each of said abutments, said supply line for said abutment of greater area including two valves in series, one valve movable into fluid-supply and fluid-cut-off positions by said device upon preponderation of said greater and lesser abutments respectively over the other, the other valve being a normally closed outlet valve, and means for opening said outlet valve coincidently with movement of one of said safety control members in motor energizing direction.

15 20. 11. A pressing machine and control mechanism as in claim 10, including means for adjustably restricting the flow through said normally closed outlet valve.

25 30. 12. In a pressing machine, a pair of coacting relatively movable pressing members, power means for causing relative approach and pressing action between said members in two phases, a first phase to cause preliminary movement into a preliminary closed position and a second phase into final closed position, two spaced safety control members for said power means adapted upon coincidental operation to cause first phase operation of said power means, a control member for causing second phase operation of said power means, a time-delay device for causing actuation of said second phase control member, and an operative connection between at least one of said safety control members and said device for starting operation of said device by actuation of said safety control member.

35 40 45 50 55 60 65 70 75 80 JAMES M. DEWEY.
